DESIGN FOR AN AUTOMATIC CATHEAD

Frank M. Owen, Houston, Tex., assignor to American Iron & Machine Works Company, Oklahoma City, Okla.

Application January 27, 1939, Serial No. 82,766

Term of patent 14 years

To all whom it may concern:

Be it known that I, Frank M. Owen, a citizen of the United States, residing at Houston, in the county of Harris and State of Texas, have invented a new, original and ornamental Design for Automatic Catheads, of which the following is a specification, reference being had to the accompanying drawing, forming part thereof, and in which:

Fig. 1 is an end elevational view of an automatic cathead, showing my new design as viewed from the right of Fig. 2; and

Figure 2 is a side elevational view.

I claim:

The ornamental design for an automatic cathead, as shown.

FRANK M. OWEN.
